US00D374184S

United States Patent

[19]

Stephens et al.

[11] Patent Number: Des. 374,184

[45] Date of Patent: **Oct. 1, 1996

[54] DC BIOPOTENTIAL MEASURING UNIT

[75] Inventors: **John D. Stephens; Seth D. Nathanson**, both of Alpharetta, Ga.; **LeRoy J. LaCelle**, New Castle, Wash.; **Ted F. Pierson; Laura Welland**, both of Seattle, Wash.

[73] Assignee: **Biofield Corp.**, Roswell, Ga.

[**] Term: 14 Years

[21] Appl. No.: 41,326

[22] Filed: Jun. 7, 1995

[52] U.S. Cl. D10/81; D10/75; D14/100

[58] Field of Search D10/75, 81; D14/100, D14/106; D24/169,165, 185, 186; 128/640, 660.07, 661, 733, 734, 745

[57] CLAIM

The ornamental design for a DC biopotential measuring unit, as shown and described.

DESCRIPTION

FIG. 1 is a perspective view of the DC biopotential measuring unit showing our new design;

FIG. 2 is a top plan view of the DC biopotential measuring unit of FIG. 1;

FIG. 3 is a bottom plan view of the DC biopotential measuring unit of FIG. 1;

FIG. 4 is a front elevational view of the DC biopotential measuring unit of FIG. 1;

FIG. 5 is a rear elevational view of the DC biopotential measuring unit of FIG. 1;

FIG. 6 is a right side elevational view of the DC biopotential measuring unit of FIG. 1;

FIG. 7 is a left side elevational view of the DC biopotential measuring unit of FIG. 1; and,

FIG. 8 is a perspective view of the DC biopotential measuring unit of FIG. 1.
